NONSKID DEVICE FOR FOOTWEAR

Giacomo Polizzi, Cuneo, Italy, assignor of two-thirds to
Edoardo Brero and Giulio Ferrero, Turin, Italy

Application October 25, 1952, Serial No. 316,883

Claims priority, application Italy October 25, 1951

2 Claims. (Cl. 36—64)

This invention relates to an improved antislipping device for boots and shoes, which may be quickly attached to or removed from the boot, or shoe and which is adjustable so as to suit various sizes of boots and shoes.

Devices of this kind are already known comprising two interlocking members, each of which has serrated or toothed flanges forming the gripping surface and each of which also has flanges at its free end to embrace the sole of the boot or shoe, together with a fastening device for holding the end flanges of the members in locking engagement with said sole.

The members of said known devices, however, are arranged and interlocked in such manner that the serrated edges of their flanges are constantly aligned with each other, whereby the possibility of their adjustment is reduced, and a certain relative movement in a transverse direction is still allowed. The main object of this invention is to provide an improved antislipping device for boots and shoes, of the type described, with a firm engagement between the movable parts avoiding any undue play or movements during use, and characterised by a wide adjustment range which cannot be obtained by the known devices.

The invention will now be described in detail with reference to the accompanying drawings, wherein:

Figure 1 is a front elevation of the device,

Figure 2 is a top plan view thereof,

Figure 3 is a bottom plan view of the same,

Figure 4 is a side elevation of the device seen from the right-hand side of Figure 1.

Figures 5 and 6 are detail side views of the two members which comprise the device.

Figure 7 is a front elevation of a modified embodiment.

Figure 8 is a plan view of the latter.

Figure 9 is a sectional view on line IX—IX of Fig. 7.

Figure 10 is a plan view of a detail of the modified device.

Figures 11 and 12 are front and side elevations of a tool for adjusting the device shown in Figures 7 to 9.

Referring now to Figures 1 to 6, 1 and 2 denote the body portions of the two cooperating members of the device.

The body portion 1 of the first member is in the form of an elongated plate of suitable metal, with downturned side portions 4 each provided with serrations 6 forming the gripping surfaces of the device. Each of the side portions 4 is bent over a short portion 4a at right angles to the body plate 1, followed by a short portion 4b parallel with the latter whereby a pair of longitudinally opposed guides 3 are formed underneath the plate 1, communicating with the channel formed between the opposed side portions 4.

The body portion 2 of the second member is likewise in the form of an elongated metallic plate in the side edges of which rows of opposed teeth 8 are cut, and which is further provided with downwardly extending side portions 5 disposed at right angles to the plate 2 and merging into it substantially along a line passing through the roots of the teeth 8.

The side portions 5 of the second member are formed at their lower edges with rows of serrations 7.

Said second member is slidably mounted within the channel formed between the side portions 4 of the first member, the upper surface of its body portion 2 being adjacent to the lower surface of the body portion 1 and the opposed outer surfaces of the side portions 5 being

2

adjacent to the opposed inner surfaces of the side portions 4, while the guides 3 accommodate the rows of teeth 8, whereby the disengagement of the two members can take place by their longitudinal displacement only.

Obviously, the height of the side portions 5 of the second member is such that the sharp edges of the serrations 6 and 7 are at the same level.

For interlocking the members of the device in a desired position to suit various sizes of boots and shoes, the first member carries secured at 11 to the parts 4a of its side portions 4 two leaf springs provided near their free ends 9a with engaging teeth 9, which are each urged into a space between two adjacent teeth 8 of the same row, and extend for this purpose through an opening 12 cut in the parts 4a and 4b of each side portion 4.

The end portions 9a form outwardly bent tongues which can be seized by the finger, when the leaf springs should be bent outwardly for disengaging the teeth 9 from the teeth 8 of the second member.

The body portions of the two members have their free ends turned upwardly at right angles thereto.

The upturned end 13 of the body portion 2 of the second or inner member forms two hooks 14; the shanks of which extend upwardly approximately the thickness of the sole A, while the upper ends of the said hooks extend inwardly a short distance on the upper side of the sole, as shown in Figure 1.

The upturned end 15 of the body portion 1 of the first, or outer member has a threaded opening formed therein, into which a set-screw 16 is screwed, carrying at one end a hook 18 provided with two tips 19 for overlapping the upper side of the sole, and a short lever 17 at its other end for turning the set-screw 16.

With this arrangement, by screwing in the bolt 16 it is possible to force the hook 18, 19 to its position on the sole end, whereby the device is rigidly held on the shoe by the hooks at each end which embrace the opposite edges of the sole, after the device has been coarsely adjusted by relative longitudinal displacement of the two members.

The upper surface of the body portion 2 of the second member has near its free end an upraised portion 20, the surface of which is situated at the same level as the upper surface of the body portion 1 of the first member, whereby the said two body portions lie parallel with the lower sole surface when the device is secured to the boot or shoe.

21 denotes a recess cut in the body portion 1 of the first member, which receives the upraised portion when the second member is fully retracted within the first member.

In the modified embodiment of the device shown in Figures 7 to 10, the two members are each U-shaped in cross-section, and comprise body portions 1 and 2 with downturned serrated side portions.

The second member is slidably mounted within the channel formed by the body portion 1 and the side portions of the first member.

Rows of aligned bores 22 of the same pitch and diameter are cut in the side portions 4 and 5 of the two members.

23 denotes a fork-shaped member, the parallel legs 25, 26 of which are so spaced that the fork may extend throughout two sets of bores in the said side portions 4 and 5 after said bores have been brought into alignment by longitudinally displacing the two members of the device.

Each of the legs 25, 26 of the fork-shaped member is formed with two peripheral grooves 24 having an axial width equalling the thickness of the side portions 5 of the second member and being cut at distances equalling the distance between the opposed inner surfaces of said side portions 5, whereby after fitting the member 23 a relative longitudinal displacement can be effected in order to prevent the fork-shaped member 23 from sliding out of the bores 22.

The sole edge engaging means are similar to those of the embodiment described above with reference to Figures 1 to 6, with the difference that the set-screw 16 is provided, instead of the lever 17, with a hexagonal head 26, and can be turned by means of a tool shown in Figures 11 and 12 in the form of a T-shaped plate, in which a hexagonal opening 27 is provided.

The upstanding leg of the tool 25 has a tapered end 25a, which can be inserted between the intermediate part of the member 23 and the side portion 1 for the purpose of assisting withdrawal of the member 23 after the set-screw 16 has been loosened for disengaging the device from the sole.

What I claim is:

1. An antislipping device for boots and shoes comprising two longitudinally aligned relatively displaceable members provided with means for engaging the opposite side edges of the sole of a boot or shoe, and with means for interlocking said members in a predetermined relative position, the first of said members being U-shaped in cross section and formed by an elongated plate with downturned serrated side portions, the second of said members being also U-shaped in cross section and formed by an elongated plate with downturned serrated side portions slidably fitted within the channel formed by the plate and side portions of said first member, said means for interlocking the two members comprising two longitudinal rows of aligned bores provided in the side portions of the first member, two longitudinal rows of

5

aligned bores provided in the side portions of the second member disposed at the same level and having the same pitch as the bores of the first member, and a fork-shaped bar having parallel legs extending through two sets of aligned bores provided in the first and second member.

10

2. Device as claimed in claim 1, wherein the fork-shaped bar is formed with two peripheral grooves in each of its legs, said groove equalling in axial width the thickness of the side portions of said second or inner member, and being spaced by a distance equalling the spacing between the inner walls of said side portions.
